W. E. WINE

FREIGHT CAR VENTILATOR

Filed Aug. 6, 1923

By

Inventor
W.E. Wine.
Parker Cook
Attorney

UNITED STATES PATENT OFFICE.

WILLIAM E. WINE, OF TOLEDO, OHIO.

FREIGHT-CAR VENTILATOR.

Application filed August 6, 1923. Serial No. 656,094.

To all whom it may concern:

Be it known that WILLIAM E. WINE, a citizen of the United States of America, residing at Toledo, in the county of Lucas and State of Ohio, has invented certain new and useful Improvements in Freight-Car Ventilators, of which the following is a specification.

My invention relates to new and useful 10 improvements in freight car ventilators and more particularly to the means employed for locking the shutters of the ventilator in their open and closed position.

Furthermore, the locking means is especially adapted for a freight car ventilator 15 of the well-known Wine type embodied in Patent No. 1,040,084 of October 1st, 1912, and in later patents on this Wine type of ventilators.

20 An object of the present invention is to so construct the shutter bar and the latch (the latter being, in turn, secured to one of the partitions between the shutters) that the shutters may be thrown to an open position and locked, and a seal passed through 25 the lock or latch, while, on the other hand, the shutters may be equally as well locked and sealed in their closed position.

Still another object of the invention is 30 to provide a locking arrangement for the shutters which is relatively simple in construction, easily applied and will withstand the shocks and strains incident to a locking mechanism employed for the freight car ventilators.

35 Another object of the invention is to provide a locking means for the shutter which is so arranged that the force of gravity will tend to hold the latch in its operated 40 position and through which latch a lead seal may be quickly and readily placed to show that the same has been properly sealed or not tampered with in transport.

With these and other objects in view, the 45 invention consists in certain new and novel arrangements and combinations of parts as will be hereinafter more fully described and pointed out in the claims.

Referring now to the drawing showing 50 a preferred form of my invention,

Fig. 1 is a fragmentary sectional view showing a portion of my standard ventilator, the two shutters being shown in section and the shutter bar and locking mechanism being shown in elevation; the shut-

ters being shown locked in their closed position;

Fig. 2 is a similar view, showing the shutters however, locked in their open position, the latch member being also shown thrown 60 back (in dotted lines) to its inoperative position;

Fig. 3 is a detailed sectional view taken on line 3—3 of Fig. 1 looking in the direction of the arrow. 65

Referring more specifically to the drawings, there is shown in section the space bars or partitions 1, as employed in my standard type of ventilator, shown in detail in Patent No. 1,040,084, while interposed 70 between the space bars or partitions are the shutters 2 which are pivoted at their opposite ends as at 3 to the sides of the frame (not shown). These several shutters are in turn operated by the shutter bar 4 75 which, when elevated, revolves the shutters to their closed position, short arms 5 being fastened to the shutter and pivoted to the shutter bar, as clearly seen in Figs. 1 and 2.

Referring now to the gist of the invention, there is shown a downwardly extending arm 6 which is formed integral with the shutter bar 4 and which is provided at its outer end with the boss and trunnions 7 as may be seen in Fig. 3. Also, on the inner surface of the shutter bar 4 is a further boss 8, the distance between the end of the arm 6 and the boss 8 and the throw of the shutter bar being such that the latch member 9, shortly to be described, may engage either of the two parts mentioned, depending, of course, whether the shutter bar is in its upper or lower position. The trunnions 7 are hollow as well as those of the boss 8 so that one may 95 register with the opening 10 provided in the latch member 9 when the latch member is in its thrown position. 90

Referring now more specifically to the latch member 9, it will be seen that it consists of the bifurcated inner end 11, so that it may be readily attached to a lug 12 formed on one of the cross bars 1 while a cotter pin may be employed to pivotally secure the same. The outer end of the latch member 9 is formed with a pocket 13, it being opened on its front, bottom and top, and has the inwardly projecting flanges 14; so that it may partly encase the trunnions 7 on the arm 6 if the shutter bar is in its 110

lowermost position or may engage the similarly formed trunnions or boss 8 formed at the lower end of the shutter bar when the latter is raised. The opening 10 in the latch member 9 is designed to respectively register with the hollow trunnions mentioned formed on the shutter bar so that a leaden seal 15 of the standard variety may be passed through the latch member and the hollow trunnions of the shutter bar.

The latch member 9 will first be thrown back out of position, as shown in the dotted lines in Fig. 2, when the shutter bar is to be operated, and when the shutters are set in their opened or closed position, the latch member will be thrown forwardly to encase either of the trunnions which will securely hold the shutter bar in its thrown position; after which the seal will be passed through the several parts, thus locking the shutters as desired.

From the foregoing it will be seen that I have provided a very efficient means for locking the shutters of a ventilator and at the same time employing a mechanism which is relatively cheap to manufacture and readily applied.

Many slight changes might be made without in any way departing from the spirit and scope of the invention.

Having thus described my invention, what I claim as new and desire to secure by Letters Patent is:—

1. A shutter bar having portions throughout its length for pivotal engagement with revolvable shutters, a short arm formed at one of said pivotal portions and a projection formed on said shutter bar between a pivotal portion and said short arm, a latch member separate from said bar and adapted to engage the arm when the bar is in one position to thereby lock the same against movement and to engage the projection when the bar is in its opposite position.

2. A shutter operating bar for freight car ventilators, said shutter bar having pivotal connections, adapted to engage revolvable shutters, said shutter bar capable of a vertical movement for opening and closing said shutters, two sets of trunnions on said shutter bar, a latch member separate from said shutter bar and adapted to engage the lowermost trunnions when the shutters are in their closed position to thereby lock the bar and shutters against movement, and said latch member likewise engaging the uppermost trunnions when the shutters are in their open position.

3. A shutter operating bar for car ventilators, said bar having pivotal connections to revolvable shutters and said bar capable of a vertical movement for operating said

shutters, a short arm formed on said bar and provided with trunnions at its outer end, the bar further provided at its lower end with a boss and hollow trunnions, a latch member having a pocket formed on its outer end and open at its bottom front and top, the forward portion of said pocket provided with inwardly extending flanges and having a transverse passageway therethrough, said latch member separate from said shutter bar and adapted to partly encase the lowermost trunnions when the shutter bar is in its raised position, to lock and hold the shutters in the closed position, the passageway registering with the hollow trunnions for the insertion of a seal, and said latch member likewise adapted to engage the trunnions on said arm when the shutter bar is raised to thereby hold the shutters in their open position.

4. A shutter operating bar for car ventilators, said bar adapted to be pivotally secured to revolvable shutters, said bar capable of a vertical movement for opening and closing said shutters, a downwardly extending arm formed on said shutter bar and provided with hollow trunnions at its outer end, said shutter bar also provided with a boss and hollow trunnions near its lower ends, a latch member having a transverse passageway therethrough separate from said bar and adapted to engage the lowermost trunnions when the shutter bar is in its raised position and to lock and hold the same and the shutters in their closed position, said passageway registering with the hollow trunnions for the insertion of a seal, and said latch member adapted to engage the trunnions on said arm when the shutter bar is raised to thereby lock the shutters in their open position.

5. A shutter operating bar for freight car ventilators, said shutter bar adapted to be pivotally connected to revolvable shutters, the bar capable of a vertical movement for opening and closing said shutters, a downwardly extending arm formed on the bar and provided with an interlocking surface at its outer end, the said bar provided with further interlocking surfaces at its lower end, a latch member separate from said bar and adapted to engage the lowermost interlocking surfaces when the shutter bar is in its raised position to thereby lock the same and hold the shutters in their closed position, and the latch member likewise adapted to engage the interlocking surfaces on said arm when the shutter bar is lowered to thereby lock the shutters in their open position.

In testimony whereof I affix my signature.
WILLIAM E. WINE.
